[57] ABSTRACT

In a cryogenic connection wherein tubular conductors insulated by a vacuum and carrying a cryogenic fluid, provides a fluid connection between the vacuum surrounding the current conducting tubular conductors with the annular cavity also subjected to vacuum pressure between inner and outer enclosures providing thermal insulation to the cryogenic connection. The coupling of connection elements is effected in a sequential conductor laying process, utilizing rectilinear sections of 20-metre enclosures and of semirigid conductor tubes of similar length.

FIG. 3

IMPROVED CRYOGENIC CONNECTION

BACKGROUND OF THE INVENTION

1. Field Of The Invention

The present invention concerns an electric cryogenic connection comprising cables insulated by a vacuum, provided with a device for subjecting the annular space which ensures the electrical insulation of the phase conducting tubes with the cryogenic connection being used for conveying high voltage electrical alternating current.

2. Description Of The Prior Art

One known type of cryogenic connection capable of conveying high voltage electrical alternating current comprises an inner enclosure, coaxial pairs of tubular conductors inside the inner enclosure with the number of pairs of conductors depending upon the number of phases of alternating current conveyed. A pair of coaxial conductors consists of an inner tubular conductor conveying a cryogenic fluid and an outer tubular conductor. The inner enclosure itself contains a cryogenic fluid which immerses the outer conductor. Vacuum is created on the one hand in the space between the inner and outer conductors, and on the other hand, in the space between the inner and outer enclosures which surround the coaxial conductors. In general, the vacuum is created independently in these two spaces which does not permit the effective vacuum pumping of the spaced formed between the inner and outer conductors, whose residual pressure, when cryogenic pumping is carried out, is due to the accumulation of helium coming very small leakages in the tubular conductors, that is, the accumulation of the cryogenic fluid flowing through the inner tubular conductor.

The aim of the present invention is to overcome these disadvantages.

SUMMARY OF THE INVENTION

The present invention has for its object the formation of a cryogenic electrical connection comprising cables insulated by a vacuum, wherein the connection comprises an inner enclosure, at least one pair of tubular coaxial conductors within the inner enclosure and constituted by an outer tubular conductor and an inner tubular conductor, means for providing cryogenic fluid flow in the inner conductor, an outer enclosure surrounding the inner enclosure and the space between the inner and outer enclosures being subjected to a vacuum pressure with the cryogenic connection being characterized by providing fluid communication between the space formed between the inner and outer conductors and the space formed between the inner and outer enclosures and therefore subjects the space between the inner and outer conductors to vacuum pressure, effecting fluid communication between these spaces and the space between the outer conductor and the inner enclosure.

An example of a cryogenic connection according to the invention ensuring the placement of the space in which a vacuum is maintained into fluid communication, will be described with reference to three diagrammatic figures. With respect to these figures, like numerals designate like components. Several devices for establishing fluid communication between those spaces subjected to vacuum pressure are provided at intervals

which are, to great advantage, spaced by 10 to 100 meters.

BRIEF DESCRIPTION OF THE DRAWINGS

5 FIG. 1 is an exploded, perspective view of a cryogenic connection provided with the arrangement for establishing fluid communication according to the invention.

10 FIG. 2a is a transverse cross-sectional view of the device of FIG. 1.

FIG. 2b is a longitudinal cross-sectional view of the device of FIG. 1.

15 FIG. 3 is a diagrammatic view of the cryogenic connection of FIG. 1, in a transversal, cross-sectional view, at the level of the central portion of the device as shown in FIG. 2.

20 Corresponding elements in these figures bear the same reference numerals.

DESCRIPTION OF THE PREFERRED EMBODIMENT

The device shown in FIG. 1 is an example of an embodiment of the invention, makes it possible to connect two sections such as 10 and 20 of a cryogenic connection within an outer enclosure 1. In each section, there are provided three pairs of coaxial tubular conductors which lie inside inner enclosure 5. Each pair of coaxial

25 tubular conductors comprise a tubular inner conductor 2, suitable for conveying a cryogenic fluid, and a tubular outer conductor 3 concentrically surrounding the tubular inner conductor 2 and spaced therefrom. Vacuum is created in the space 4 between the inner and outer conductors and between the outer enclosure 1 and the inner enclosure 5 while a cryogenic fluid immerses outer conductor 3 and flows between the inside of the inner enclosure 1 and outer conductors 3. The figures show three pairs of tubular coaxial conductors, by way of an example of the embodiments of a cryogenic connection which is able to convey a three phase

30 alternating current.

35 The inner conductor 2 constitutes the "phase conductor", whereas the outer conductor 3 constitutes the "neutral conductor". The vacuum created in the space 6 which separates the inner enclosure 5 from the outer enclosure 1 provides a good thermal insulation for the cryogenic connection. With respect to the coaxial tubular conductors, the inner and outer conductors 2 and 3 respectively are separated by means of insulating

40 spacers such as spacers 19. The insulating spacers 19 are formed by the thermal assembly of two sectors and their function is to contain the electro-dynamic efforts exerted between the inner and outer conductors, and contribute to the electrical insulation by the vacuum

45 existing between the inner and outer conductors, the limiting of the thermal losses between the outgoing helium circuit within the inner conductors and the return helium limit to the inside of the inner enclosure 5, while allowing for limited vacuum pumping impedance and enabling the inner and outer conductor tubes to fit together and the sliding of the group of inner and outer conductor tubes. These spacers are installed remote

50 from the site of assembly and that is at their point of manufacture before the inner and outer tubes, for example, 20-meter tubes are fitted together. The pairs of coaxial conductors 2 are corrugated tubes made of

55 copper covered with a niobium deposit which is polished, then covered, for example, with polytetraflu-

60

65

orethylene. The aim of this manufacturing technique is to protect the niobium layer mechanically when assembling and to protect the niobium layer at the level of the insulating spacers 19 when subjected to vibration associated with electrodynamic forces and to improve the dielectric strength and to reduce the ionizing currents taking into account the angle of losses of the polytetrafluorethylene which is less than that of other dielectrics at a temperature of 5 ° Kelvin.

The outer conductors such as 3 are free of corrugations, that is, they are cylindrical over a short portion of their length, that is, approximately one meter. They have in their corrugated portions a diameter whose bulk is slightly less than that of the their cylindrical portions. They may be fitted without difficulty over a portion of their length into cylindrical tubes 110 which form a part of the assembly 100, according to the invention, the tubes 110 having a diameter slightly greater than the diameter of the conductors 3 at their cylindrical portion. The cylindrical portions of the tubes 3 lie within assembly 100 and are now shown in FIG. 1. The assembly 100 comprises on the one hand two identical flanges 119 and 120 which at their peripheries are provided with rims 121 and 122 respectively welded to the ends of inner enclosure 5 for sections 10 and 20. On the other hand, at least three tubes such as 101, 102 and 103, have ends welded respectively to the flanges 119 and 120 to permit fluid communication between sections 10 and 20 of the connectors. Furthermore, cylindrical tubes such as 110, 111 and 112 are provided at spaced circumferential positions, the number of tubes being equal to the number of pairs of conductors, with respective tubes receiving the pairs of coaxial conductors. The "outgoing" flow of cryogenic fluid occurs within the inner conductor tubes, while the "return" flow of cryogenic fluid occurs within the space between the outer conductors 3 and the inner enclosure 5.

At a position defined by the assembly 100, helium flow on the inside as defined by flanges 119 and 120, is limited to the set of tubes 101, 102, 103, 110, 111, and 112, and limited on the outside by the space between the outer conductors 3 and the inner enclosure 5 with the outer faces of flanges 119 and 120 being subjected to helium pressure. The helium circuit is therefore as follows: three "outgoing" tubes consisting of the three inner conductor tubes 2 between the cooling means and a connection to the helium "return" circuit, a "return" tube by the space between the outer conductors 3 and the inner enclosure 5, in turn connected to the cooling means (not shown). The choice of material is particularly important in that type of device because of the electrical and mechanical stresses. By way of example, this choice is made as follows: the end flanges 119 and 120 and the cryogenic flow tubes 101, 102 and 103 are made of an iron and nickel alloy containing 30 to 45 percent nickel; that alloy being, for example, of a type known in France by the trade name "INVAR". The tubes such as 110, 111, 112 surrounding each pair of coaxial conductors have their ends 14 and 15 made of INVAR, whereas their intermediate portion 12 may be made of copper. That structure may be formed, for example, by means of an electro-forming method.

The tubes such as 101, 102, 103 made on INVAR which ensures that the greater part of the cryogenic fluid flow is liquid helium flow, for example, also allow

the transfer of longitudinal mechanical tensile stresses existing in sections 10 and 20 of the connectors to be made of INVAR whose rectilinear shape gives rise to no reduction in its length when cooling is effected.

The present invention is directed to the communication of spaces 4 and 6 which may be subjected to common vacuum. In this regard, by reference to FIG. 3, an orifice 90 of oblong shape is formed in the central copper portions within each of the tubes 110, 111 and 112, the axis of that orifice being parallel to that of the tubes and situated on an accessible face of that tube which forms a part of the connection. An orifice 91 whose shape is oblong, having dimensions smaller than that or equal to that of orifice 90 is formed in the outer conductor for each of the tubes 110, 111 and 112, these orifices being in each case the other's extension. A local deformation 92 of the tubes 110, 111 and 112 puts the rim of the orifices 90 in contact with the outer conductor tubes 3 and a weld 17 is provided between the copper tubes around the perimeter of the orifice 90.

Since the axis of the orifice is of oblong shape and is parallel to that of the conductor, the currentlines in the conductors are not greatly disturbed in the vicinity of that orifice and do not give rise to any appreciable electrical losses at that point. Moreover, the helium flow in the annular space between the outer conductor 3 and the tube 110 is not greatly disturbed, subsequent to the direction of the axis of the orifice, the stabilization of the supraconductor of the conductor tube 3 is ensured, while the heat exchange between the conductor 3 and the flowing helium remains satisfactory throughout virtually the whole perimeter of the tube 3. The arrangement for communicating spaces 4 and 6 is best seen in FIG. 3 which is a transverse cross-sectional view of assembly 100 seen in FIG. 1. FIG. 3 effectively shows the weld at 17, for each pair of coaxial conductors, with this weld connecting together the edges of the orifices 90 which are oblong shaped formed in the outer conductor 3 and in the duct 112 and thus enabling the space 4 between the inner conductor 2 and outer conductor 3 to communicate with the space 6 between the inner enclosure 5 and outer enclosure 1. It is quite obvious that there is a weld such as 17 for each pair of coaxial conductors. The vacuum may thus be common to spaces 4 and 6 and a single pumping means (not shown) and coupled to connection via tube 16 is all that is necessary to provide the desired vacuum pressure. The structure has, however, the advantage of insuring without discontinuity, the cooling of the outer conductors of each pair of coaxial conductors. Indeed, the cryogenic fluid which flows in the inner enclosure and passes through tubes 101, 102 and 103 and also flows within tubes 110, 111, and 112, round the outer conductor 3. That figure also shows the intermediate portion of copper and an end portion 15 made of INVAR, of the tube 112. When laying, the three pairs of coaxial conductors 2, 3, are inserted in the three tubes 110, 111, 112, made of INVAR and copper, and pass through the assembly 100 defined by flanges 119 and 120. One of the flanges 119 made of INVAR has its rim welded to the end of the inner enclosure 5 which is made of INVAR and contains the pairs of conductors. In the space between flanges 119 and 120, an orifice having an oblong shape is then formed on each of the outer conductors and on each of the tubes 110, 111 and 112, and the welding of the edges of the two ori-

fices thus formed is effected thereon, the edges of these orifices being made of copper. This method therefore enables the spaces under vacuum to be in fluid communication with each other, while the conductors remain in contact with the helium without discontinuity at the point of each connection.

The ends 14 of the tubes 110, 111, 112 made of INVAR are easily welded to the flanges 119, 120 and which are also made of INVAR. The vacuum may then be created simultaneously in the spaces 4 and 6 by pumping means (not shown) connected to the pipe or tube 16 leading into the enclosure 1 through openings 7, 8 and 9 formed by weld 17 at the edges of the orifices 90 and 91.

The assembly of the connection elements which is achieved in terms of the described embodiments of the invention is effected as follows: the assembly 100, comprising six tubes 101, 102, 103, 110, 111, 112 and flanges 119, 120, is produced at the factory by welding the tubes to the flanges on the accessible faces of the latter. The adjacent 20 meter sections of pairs of coaxial tubular conductors 2 and 3 are welded to the pairs of conductors previously installed, then put together in a rectilinear configuration. A tubular element of the inner enclosure 5 in terms of section 10 or section 20 is installed, then welded to the elements of the connection previously installed. For section 10, the inner enclosure 5 surrounds the three pairs of conductors 2, 3, these conductors extending past the free end of section 10 by a length greater than 10 meters. The device or assembly formed by tubes 101, 102, 103, 110, 111, 112 and flanges 119 and 120 is installed by inserting the free ends of the coaxial conductors and sliding them over 10 to 20 meters until flange 119 comes into contact with the end of the inner enclosure 5 forming section 10. This enables the welding of the rim of the flange 119 and the inner enclosure 5 for section 10. The conductors 2, 3 have a corrugated free portion 10 to 20 meters long extending past the connection point defined by the flange with the ends of these conductors possibly being set apart from each other, thus enabling circumferential welding of the pairs of conductors to a further section of 20 meter conductors. These later conductors 3 are then put together in a rectilinear configuration. A second section 20 constituting a further 20 meter section of the connection is then installed by connecting the inner enclosure 5 of that section to flange 120. This is achieved by welding the rims or peripheries of flange 120 and inner enclosure 5 of section 20 together since they are both made of INVAR. Inner enclosure 5 of section 20 surrounds the pairs of conductors over a portion of their length. The following stage of assembly is then effected by joining in alternative fashion, 20 meter enclosure elements to 20 meter conductor elements, the respective connections being staggered with respect to each other. Lastly, the orifices of an oblong shape are subsequently formed in the outer conductors such as 3 and the edge of these orifices is welded to the edge of orifices formed in tubes 110, 111, 112, FIG. 2, this being done before the installing of the outer enclosure 5 of the connection and possibly before installing of a thermal screen.

The assembling method which has just been described is compatible with the minimizing of the diameter of the enclosures, by means of the staggering of the positions at which the connections of the conductors are formed and of the positions at which the connec-

tions of the enclosures are formed. That minimizing of the diameter of the inner enclosure 5 remains unchanged at the point of connection between parts, this being made possible by the ease of access, in three directions, spaced circumferentially 120° apart, for forming oblong orifices and welds at that point, when the tubes are put together. This is made easier, due also to the possibility of opening the end of the conductors which are semi-rigid, a judicious choice of their structure enabling electrical connections to be formed before regrouping these conductors.

Connections for dividing the vacuum applied to the cryogenic electrical connection into sections (not shown) are arranged, for example, every 400 meters.

Their mechanical function consists in ensuring the fixing of the coaxial conductors of the inner enclosure 5 enabling the connection between 400 meter connection sections forming an angle between them. This fixing is necessary subsequent to efforts generated by cooling and possibly by the existence of declivities. The function of these connections with respect to the pumping is to enable the creation of a vacuum which is not simultaneous in the 400 meter sections, during the installing of the connections, to limit the extent of the zones affected by leakages, to enable increased pumping at that point in the connection and detecting of leakages as well as their repair.

The connection between the inner and outer conductors at that point is effected by means of insulating cross-pieces. These cross-pieces comprise a voltage distributor of the capacitative type formed by divided conductors embedded, for example, in a phenolic resin; the insulating cross-pieces being semi-fluid-tight, that is, capable of holding a primary vacuum when one of the faces is subjected to atmospheric pressure. That characteristic therefore remains compatible with their vacuum dividing function.

It is quite obvious that in the structure which has just been described, the means used may be replaced by equivalent means, ensuring the same technical functions and that the materials used may be replaced by materials having the same mechanical and electrical properties without going beyond the scope of the invention.

What is claimed is:

1. In a cryogenic connection of the type comprising:

an outer enclosure,

an inner enclosure within said outer enclosure and spaced therefrom,

means for subjecting the space between said outer enclosure and said inner enclosure to a vacuum, means for providing a cryogenic fluid flow in said inner enclosure,

at least one pair of tubular coaxial conductors inside said inner enclosure and sealed therefrom, said pair of coaxial conductors being constituted by an outer tubular conductor and an inner tubular conductor,

means for providing a cryogenic fluid flow in said inner tubular conductor, and

means for subjecting the space between said inner and outer tubular conductors to a vacuum, the improvement comprising:

means for providing communication between the space formed between said inner conductor and said outer conductor and the space formed be-

tween said inner enclosure and said outer enclosure without communicating with the space formed between said outer conductor and said inner enclosure.

2. The cryogenic connection according to claim 1, wherein said common means for communicating the space between said inner conductor and said outer conductor and the space between said inner enclosure and said outer enclosure, on the one hand comprises a first orifice formed in the wall of said outer conductor and on the other hand a second orifice formed in a tubular wall surrounding said outer conductor and forming a tight continuation of said inner enclosure, the edges of these two orifices being connected to each other in a fluid tight manner over their complete length.

3. The cryogenic connection according to claim 2, wherein: said first and second orifices have an oblong shape whose greatest dimension extends in the longitudinal direction of the conductors.

4. The cryogenic connection according to claim 2, wherein said inner enclosure comprises two sections separated by an assembly, said assembly comprising: two flanges whose peripheries are sealed respectively to the end of said sections of said inner enclosure and defining a fluid tight chamber therebetween, at least one tube extending in a fluid tight manner between said flanges for permitting the flow of cryogenic fluid between sections of said inner enclosure, said tube connecting orifices formed within said flanges and tubes surrounding each of said outer conductors and forming a cryogenic flow path about said outer conductor be-

tween sections of said inner enclosure, and wherein said second orifice is formed in the tubes surrounding said outer conductor in each instance, adjacent to said first orifice with the edges of the first and second orifices being in contact with each other by bringing the walls of the outer conductor and the tube surrounding said outer conductor together and being sealably joined together by means of a weld.

5. The cryogenic connection according to claim 4, 10 wherein: said first and second orifices have an oblong shape whose greatest dimension extends in the longitudinal direction of the conductors.

6. The cryogenic connection according to claim 4, 15 wherein: said flange, said inner enclosure, said flow tube and at least the ends of each tube surrounding said outer conductor are made of an iron and nickel alloy containing 30 to 45 percent nickel.

7. The cryogenic connection according to claim 6, 20 wherein: said first and second orifices have an oblong shape whose greatest dimension extends in the longitudinal direction of the conductors.

8. The cryogenic connection according to claim 6, 25 wherein the intermediate portion of each tube surrounding each outer conductor is made of one material from the group consisting of aluminum and copper.

9. The cryogenic connection according to claim 8, 30 wherein: said first and second orifices have an oblong shape whose greatest dimension extends in the longitudinal direction of the conductors.
